Patented Sept. 30, 1919.

Urban S. Alsrue,
INVENTOR.

By *Chapin Attegnan*
ATTORNEY.

UNITED STATES PATENT OFFICE.

URBAN S. ALSRUHE, OF TOWSON, MARYLAND.

BUILDING CONSTRUCTION.

1,317,471.

Specification of Letters Patent. Patented Sept. 30, 1919.

Application filed June 6, 1918. Serial No. 238,471.

To all whom it may concern:

Be it known that I, URBAN S. ALSRUHE, a citizen of the United States, residing at Towson, in the county of Baltimore and State of Maryland, have invented certain new and useful Improvements in Building Construction, of which the following is a specification.

My invention is an improvement in buildings, and relates more especially to the particular construction of the walls of a building in which is employed framing material and a filling to add stability to the structure.

The primary object of my invention is to provide a wall construction for frame houses which may be easily, conveniently, and cheaply built, using principally rough or cheap lumber in connection with the usual outside weatherboarding finish, and a filling of a cheap composition which will add strength and stability to the structure, the peculiar construction also greatly facilitating the application of the inside finish and trim in the completion of the house.

A further object of my invention is the production of a wall construction for frame houses which is of extraordinary strength to withstand high winds, which will provide suitable insulation against heat and cold, will prevent the presence of mice and insects, will permit nails to be driven into the interior surfaces of the walls without breaking the plaster, and will minimize the danger of fire as well as retard the progress of a fire that may start at any point.

Other objects and advantages of my invention will hereinafter appear in the specification, and what I particularly claim as new and desire to secure by Letters-Patent is more specifically set forth in the appended claims.

In the accompanying drawings which form a part hereof:—

Figure 1 is a front elevation of a part of the outer wall of a frame house constructed in accordance with my invention.

Fig. 2 is a sectional view through one of the outer walls and first floor, to illustrate the manner of construction.

Fig. 3 is an enlarged detail sectional view through the lower part of the wall to more clearly show the construction thereof.

Fig. 4 is a transverse sectional view, on the line 4—4 of Fig. 3. 55

Like numerals of reference indicate like parts in all the figures of the drawings.

In building a house carrying out my invention a foundation wall, 1, is first constructed in the usual manner, either of brick as shown in Fig. 1 or of cement as indicated in Fig. 3, and upon this wall the usual sill pieces 2 are laid or embedded. The joists 3 for the first floor may be now set in place with their ends resting on the sill pieces, and flooring-boards 5 laid on said joists to provide the permanent floor, or rough boards laid temporarily to stand upon in putting up the studding 7 and building the superstructure. Of course the construction so far described is common to all frame buildings, but in arranging the studding I purpose placing them approximately three feet apart to economize material, without sacrificing stability in the present instance, and so as to facilitate the placing of doors and windows. 70 75

The studding or uprights 7 are held in place by nailing them to the sill pieces and connecting them on a line with the second floor by the usual horizontal pieces which support the second-floor joists, after which the window frames 8 and door-frames 17 are set in between the studding and nailed thereto. This frame-work construction may be carried to the desired height and the roof put on, and by applying the weatherboarding 9 the building will be inclosed so that inclement weather will not interfere with the operation of completing the wall structure which I will now particularly describe. 80 85 90

By reference to Fig. 3 it will be noted that the first joist, next to the wall, fits closely against the inner edge of the adjoining sill-piece and that the flooring projects over to the studding, forming an enlarged pocket to receive the filling material, hereinafter described, so as to provide a firm anchoring-base as well as to exclude mice and insects. Similar pockets are formed between the ends of the joists by nailing small pieces, 4, of thin cheap board, or odds and ends, to the sill pieces between the joists, as shown in Fig. 3. Boards 10 are now nailed to the inner side of the studding immediately above the flooring 5, about 95 100 105

two widths being applied at first, and then what I term "anchor-laths" are secured in place, preferably wedged in between the boards to reinforce them, being in the 5 present instance triangular in cross-section, and these laths also serve to properly key the plaster-coat 13, which is later applied to finish the interior wall. When the two widths of boards 10 and their companion 10 anchor-laths 12 are nailed in place a composition or mixture of cement and sand is deposited in the spaces formed by the studding, weatherboarding and inside boards, after which several more widths of inside 15 boards and their anchor-laths are applied and the additional spaces so provided filled with the mixture on top of the first batch, and so on to the height of the wall. It will be understood that this work of applying 20 the boards 10, laths 12 and mixture 11 may be done by unskilled labor, and that the partition walls of the house are built in the same manner, using thinner studding or pieces of scantling to reduce the thickness 25 of the filling; but in building up the partitions boards and laths are secured to both sides of the studding as no weatherboarding is used. After the walls and partitions are built up in this manner the inside walls are 30 finished by the coating of plaster, 13, which is securely keyed in the dovetailed recesses between the laths and thinly covers the outer surfaces of said laths. The walls are then ready to receive the trim, such as the 35 washboards 16, door-casing 18, &c.

Rough or common boards may be and preferably are used as the boards 10, and unplaned strips of cheap material used to form the anchor-laths 12, inasmuch as these 40 parts are concealed by being embedded in the filling 11 and finishing plaster-coat 13. Also a cheap filling mixture is used, consisting of about one part cement to fifteen parts sand, and I have found it is not necessary 45 to use best-grade sand, for coarse dirt may be substituted, providing a much cheaper filling possessing the required hardness to insulate the house from the effects of heat and cold, prevent dampness, and exclude 50 rats, mice and insects. Instead of the cement and sand I may use lime and sand or coarse dirt, and may use red clay to fill in and make a solid wall.

By the wall construction hereinbefore 55 described no permanent braces are required between the studding—the mortar or filling binding the woodwork together to provide a firm integral structure—but to keep the weatherboarding from warping and in 60 shape between the studding, strips 20 are interposed and secured to the inner side of the weatherboarding by nails or screws from the inside, said reinforcing strips being

about an inch thick and the mortar fills in around them. Sheathing paper also may be 65 used next to the weatherboarding.

The surface coat of plaster is firmly held to the boards and laths, and therefore nails may be driven into the wall without cracking the plaster. Nails may be driven into 70 any part of the wall and secure a good hold, as they will penetrate into either the boards 10 or the anchor-laths 12.

A house built in accordance with my invention, after the manner hereinbefore described, may be put up very quickly and cheaply, and the structure will be equally 75 as strong as a brick house possessing similar advantages in withstanding high winds, heat and cold, and will be even more effective 80 in preventing dampness penetrating the wall. Therefore I provide for constructing a substantially-built house that may be put up very cheaply principally by unskilled labor, and will have the general 85 appearance of a more expensive construction, while at the same time possessing advantages over both the ordinary frame and brick houses.

Having described my invention, I claim: 90

1. A wall construction for houses and other buildings, comprising studding rising from the foundation and spaced apart a suitable distance, weatherboarding secured to the outer side of the studding, boards secured to the inner side of the studding, laths triangular in shape and secured to the said boards with a flat side outermost and one edge projecting between said boards and filling material with a cement binding embedded between the studding, weatherboarding and inside boards, substantially as shown and for the purposes set forth. 100

2. A wall construction for houses and other buildings, comprising a foundation wall, sill pieces laid thereon, studding rising from the sill pieces and spaced apart a suitable distance, weatherboarding secured to the outer side of the studding, rough boards secured to the inner side of the 105 studding, rough laths triangular in shape and secured to the said boards with a flat side outermost and one edge projecting between said boards, filling material with a cement binding embedded between the studding, weatherboarding and inside boards, and a finishing coat of plaster applied to the inside boards between the laths and over the latter, substantially as shown and for the 110 purposes set forth. 115

In testimony whereof I affix my signature in the presence of two witnesses.

URBAN S. ALSRUHE.
